UNITED STATES PATENT OFFICE.

JOHN K. BEEHLER, OF ERIE, ILLINOIS.

HARVESTER ATTACHMENT.

SPECIFICATION forming part of Letters Patent No. 450,443, dated April 14, 1891.

Application filed November 5, 1889. Renewed January 16, 1891. Serial No. 378,027. (No model.)

To all whom it may concern:

Be it known that I, JOHN K. BEEHLER, a citizen of the United States, residing at Erie, in the county of Whiteside and State of Illinois, have invented certain new and useful Improvements in Harvester Attachments; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to an improvement in harvester attachments; and it consists in the peculiar construction, combination, and arrangement of parts, as will be hereinafter fully described, and afterward specifically 20 pointed out in the claims hereunto annexed.

The object of my invention is to provide a device whereby the machine can be readily and easily turned at right angles.

Referring to the drawings, wherein like 25 letters of reference indicate corresponding parts wherever they occur, Figure 1 is a perspective view of the device attached to the tongue of the machine. Fig. 2 is a top plan view showing in dotted lines the position of 30 the tongue when making a square turn. Fig. 3 is a section through the hinge of the horse-detacher.

Referring to the drawings by letters of reference, A is the tongue of a harvesting-machine, having secured on its end two plates a' and a'', which extend beyond the same, and having pivoted loosely on the top a bell-crank b. This bell-crank has a perforation in the horizontal position, which receives the king-bolt b', and a cord or rope c is attached to the vertical portion. The other end of this cord or rope is placed within easy reach of the driver, so in case of the horses becoming unmanageable the driver may pull the cord raising the 45 king-bolt, which passes through the coupling-block out of engagement with the same, thus releasing the horses from the machine and preventing any serious damage being done to the same.

50 B is an axle having two wheels secured on

its ends. To this axle is secured the tongue c, to which the horses are attached. On this axle B are two braces D, which extend rearwardly and converge, forming bearings for the shaft e of the coupling-block E. Said 55 coupling-block forms a bearing for the king-bolt c, which enables the tongue A of the machine to rest in a universal joint, preventing all horse motion being conveyed to the machine and the horses from receiving any jolt 60 from the machine.

F indicates guard-plates secured on the top and bottom of the axle and extending out at the bent portion a sufficient distance to prevent the tongue A from rubbing the wheel, 65 as shown in dotted lines in Fig. 2.

G indicates a draft-equalizer of ordinary construction, pivoted at g to a brace H, said brace H being secured to the tongue c, and itself being braced by pieces I. The draft-equalizer is pivoted in a direct line with the tongue A, and the braces I tend to make the draft direct with the tongue A without any tension or strain on the brace H.

I am aware that many minor changes may 75 be made in the construction and arrangement of the parts without in the least departing from the nature and spirit of my invention.

Having thus fully described my invention, what I claim, and desire to secure by Letters 80 Patent, is—

1. The combination, with a harvesting-machine, of the truck pivotally secured to the tongue thereof, rearwardly-extending braces secured to the truck, and a block journaled 85 in the braces, substantially as described.

2. The combination, in a harvesting-machine tongue having projecting plates on its upper and lower face, of a truck having two rearwardly-extending braces, a block 90 journaled in the braces, to which said plates are pivotally secured, and the guards F, substantially as described.

In testimony whereof I affix my signature in presence of two witnesses.

JOHN K. BEEHLER.
